COAXIAL ROTARY JOINT

Frank W. Yeagley, Dallas, Tex., assignor to Continental Electronics Manufacturing Company, Dallas, Tex., a corporation of Texas

Application April 3, 1958, Serial No. 726,174

8 Claims. (Cl. 174—21)

The present invention relates to a coaxial cable rotary joint.

Coaxial cables for transmitting radio waves may be required to have rotary joints in order to permit one portion of the cable to rotate with respect to the other portion. Such rotary joints may be needed, for example, where the cable is connected to a rotating load, such as a rotatable antenna. It is desirable that such rotary joints should make good contact and prevent leakage of the radio frequency field. The joint should also by reason of its good contact avoid sparking or corona effects. It is desirable that the joint should physically close the cable, so as to prevent contamination thereof. Another desirable feature of a rotatable joint adapted to rotate continuously is that it shall have minimal wear and a very long life. Still another desirable characteristic is a low standing wave ratio.

It is an object of this invention to provide a rotary coaxial cable joint which has all of the above-mentioned desirable characteristics.

Another object of the invention is to provide a rotary joint which is simple and inexpensive in construction and permits very easy assembly of the cable at the joint.

The above and other objects and advantages of my invention will be apparent from the following description and the accompanying drawings, in which:

Fig. 1 is a cross sectional view of one embodiment of my invention;

Fig. 2 is a view of a flat layout of one of the connectors of my invention; and

Fig. 3 is a view of the outline of the tapered connectors.

Fig. 1 of the drawings shows a coaxial cable 10 rotatably connected to a like coaxial cable 12. These cables may have inner and outer conductors 14 and 16 and conductors 18 and 20. The inner conductors having the same diameter and the outer conductors having the same diameter. The outer conductors terminate adjacent each other at 21 and the inner conductors terminate adjacent each other at 22. The conductors are circular cylinders. Outer conductor 16 is provided with a connector 24 conductively fastened thereto in any suitable manner, such as by soldering indicated at 26. Connector 24 is preferably formed of a resilient metallic material of high conductivity and extends a variable distance into conductor 14 and is in good conductive contact therewith. A conductor 18 is similarly fastened to a conductor 28 by any suitable means such as soldering 30.

The connector 24 is provided with a series of parallel axially extending slots 32 at one end defining a like plurality of contact fingers 34 which are preferably of equal width and substantially equal length. Connector 28 is similarly provided with a regular series of parallel axially extending slots 36 defining resilient contact fingers 38. The contact fingers 34 may have sufficient resilience to provide firm contact with conductor 14 and fingers 38 of connector 28 may similarly provide firm contact with inner conductor 20. If desired, however, the contact fin-

2

gers may each carry a contact button 40 made of a special material for use as a sliding contact, such material being chosen for its compatibility with the material of the solid conductor upon which it slides. Certain sintered contact materials, such as silver and graphite compounds, or tungsten and graphite compounds, are available and useful as contact buttons. The contact buttons may be fastened to the contact fingers in any suitable manner.

A feature of the invention is that each of the connectors terminate in a helical curve 42 and 44, so that each contact finger extends to a different point along the length of the coaxial cable. This staggered, or tapered, or helical arrangement of the contact fingers enables each individual finger or contact thereof to have its own contact area on the solid conductors 14 and 20. Hence, during rotation, each contact will travel over a different path so that all of the contacts do not wear a single annular path around the conductors 14 and 20. This construction, therefore, provides a considerable improvement with regard to the life of the rotary joint. Also, the tapered or spiral arrangement of the contacts provides a more gradual transition from one inner conductor to the other and from one outer conductor to the other than that would be obtained if all contacts were in the same annular path. Connectors 24 and 28 may be formed so that their terminations, as defined by curve 42 and 44 extend over a considerable fraction of a wavelength, for the purpose of producing a gradual transition or junction between the conductors in order to achieve less discontinuity and a smaller standing wave. The connectors having a helical termination have a flat layout which is shown in Figure 2 and may be formed of a single flat strip of the shape shown in Figure 2. The strip 24 or 28 is simply cut on the bias 46 and then suitably slotted to form the contact fingers. When rolled up, the connector will then have the desired helical or spiral form, an outline of which is shown in Figure 3.

Although I have shown only one embodiment of my invention, in order to simply illustrate the principles thereof, it will be evident to those skilled in the art that many variations and modifications thereof may be made within the spirit and scope of my invention as defined in the following claims.

I claim:

1. In combination, first and second connected aligned coaxial radio frequency transmission lines each having inner and outer cylindrical conductors, one of the outer conductors having an extension telescoped into the other outer conductor, said extension having a tapered length, one of the inner conductors having an extension surrounding the other inner conductor and having a tapered length.

2. Apparatus according to claim 1 wherein said conductors have circular cross-sections and said extensions resiliently and rotatively engage said other conductors to form a rotatable joint between said first and second transmission lines.

3. A coaxial cable rotary joint comprising a first portion and a second portion having telescoped first and second inner conductors and telescoped first and second outer conductors, said first inner and outer conductors

each having electrical contacts near the end thereof frictionally and rotatably engaging said second inner conductor and outer conductor, respectively, the contacts being disposed to make contact on each of said second conductors at different points along the length thereof.

4. A rotary joint according to claim 3, wherein the contacts of the inner and outer conductors are arranged helically.

5. A rotary joint according to claim 3, wherein each first conductor includes a connector formed of resilient material and conductively fastened at one end to said first conductor, said connector being tapered at its other

end, said other end being slotted in the axial direction to form resilient contact fingers engaging the corresponding second conductor.

6. A rotary joint according to claim 5, wherein the connector for the outer conductors is therewithin and the connector for the inner conductors surrounds said inner conductors.

7. A rotary joint according to claim 5, wherein the connectors taper over a considerable fraction of a wavelength of the wave adapted to be transmitted by the co-axial cable.

8. In combination, first and second coaxial high frequency transmission lines each having inner and outer cylindrical conductors, both inner conductors and both outer conductors being in axial alignment, one of the outer conductors being telescoped into the other outer conductor a distance which varies round its circumference, said one outer conductor being in contact with the inner wall of the other outer conductor, one of the inner

5

10

15

conductors having an end which surrounds the other inner conductor and extends therewithin a distance which varies round the circumference of said inner conductors, said end of said one inner conductor being in contact with the outer wall of the other inner conductor.
